(57) **CLAIM**

The ornamental design for a stations of the cross article, as shown and described.

DESCRIPTION

FIG. 1 is a front elevational view of the present invention showing the new design.

FIG. 2 is a back elevational view of the present invention shown in FIG. 1.

FIG. 3 is a top view of the present invention shown in FIG. 1.

FIG. 4 is a bottom view of the present invention shown in FIG. 1.

FIG. 5 is a right side view of the present invention shown in FIG. 1.

FIG. 6 is a left side view of the present invention shown in FIG. 1.

FIG. 7 is a front, top perspective view of the present invention shown in FIG. 1.

FIG. 8 is a front, bottom perspective view of the present invention shown in FIG. 1.

FIG. 9 is a back, top perspective view of the present invention shown in FIG. 1; and,

FIG. 10 is a back, bottom perspective view of the present invention shown in FIG. 1.
